SEWING MACHINE PRESSER FOOT ATTACHMENT

Filed Jan. 20, 1930

FIG. 1.

FIG. 2.

FIG. 3.

INVENTOR:

ZACHARIA ROUTTENBERG,

BY: Otto D. Ringer,
his Atty.

UNITED STATES PATENT OFFICE

ZACHARIA ROTTENBERG, OF LOS ANGELES, CALIFORNIA

SEWING MACHINE PRESSER FOOT ATTACHMENT

Application filed January 20, 1930. Serial No. 422,048.

This invention relates to devices used on the presser-foot of a sewing machine to guide the operator in sewing in a certain manner.

One of the objects of this invention is to provide an attachment which can easily be slipped over the end of a presser-foot and being designed to guide the edge of one material in a certain relation to another material.

Another object is to provide an attachment made of a single piece of material bent to snugly fit around the end of a presser-foot and having a rolled-in edge to be on the underside of the presser-foot when the attachment is in operative position.

Other objects will appear from the following description and appended claim as well as from the accompanying drawings, in which—

Fig. 1 is a side elevation of a simple presser-foot of a sewing machine of which the underside of the front end is set off or back so that the underside of an attachment comes flush with the remaining portion of the foot, an attachment being indicated in section on line 1—1 of Fig. 2.

Fig. 2 is a top plan view of the attachment in proper position on the front end of a presser-foot of which only a portion is indicated in this illustration.

Fig. 3 is a cross section on line 3—3 of the attachment illustrated in Figs. 1 and 2, a narrow strip of material being also indicated in proper relation to the attachment and above and in a certain relation to another piece of material.

In the use of a sewing machine two or more pieces of different materials are frequently stitched together and preferably in a straight or evenly appearing manner, as, for instance, by a parallel stitching near one of the edges of a narrow strip of material to fasten this strip to another piece of material, as roughly indicated in Fig. 3, where the strip 4 is disposed under the presser-foot 5 and with one edge guided by and within the rolled-in end 6 of the attachment 7.

The presser-foot 5 is always in a certain relation to a needle in any sewing machine,

in the illustration of Fig. 3, a portion of a needle being indicated at 8.

By this arrangement, if the strip 4 is to be stitched to another piece of material 9, the ordinary operation of the needle 8 will result in a stitching evenly along the edge of the strip 4 at about the point indicated at 10 whereby the strip 4 is secured to the material 9.

In the preferred form in which the attachment is illustrated in the drawing it is made of a single piece of material bent to firmly engage around the presser-foot. Beginning with the rolled-in end 6, the bend at 11 serves to align the attachment against the edge 12 of the presser-foot 5, the attachment extending thence over the underside of the presser-foot, being again bent at 13 to align the attachment against the edge 14 of the presser-foot, and another bend at 15 brings the upper portion 16 of the attachment over the top side of the presser-foot.

The attachment is, of course, made of thin material and preferably spring-like to assure a clinching of the attachment to the presser-foot, the comparatively heavy showing in the drawings being merely used to facilitate an illustration in section.

Though thin material would not materially interfere with the proper sewing operations even in the portion of the attachment below the presser-foot, the presser-foot in its front end is reduced or cut down as indicated at 17 in Fig. 1 so that the underside of the attachment becomes flush with the underside of the larger or remaining portion of the presser-foot.

At the same time this off-setting of the presser-foot forms a shoulder 18 against which the attachment abuts, adding to the aligning facilities of the attachment on the presser-foot besides the aligning along the opposite side edges of the presser-foot, referred to and explained above.

Inasmuch as material is generally pushed or moved in the direction of the arrow 19 under the presser-foot the shoulder 18 serves also to prevent a pushing of the attachment over the presser-foot beyond a desired point.

Having thus described my invention, I
claim:

A sewing machine attachment comprising
a unitary member of substantially U-shaped
cross section adapted to slip endwise over the
front-end of a presser-foot, the free end of the
lower shank of the U-shaped member being
rolled in and being also bent upwardly before
this rolled-in end, providing a material edge
guiding channel and a shoulder for precluding
lateral displacement of the member relative
to the presser foot.

In testimony that I claim the foregoing as
my invention I have signed my name.
